(57) **CLAIM**

We claim the ornamental design for a display screen with graphical user interface, as shown and described.

DESCRIPTION

FIG. 1 is a front elevation view of a display screen with graphical user interface showing a first embodiment; and, FIG. 2 is a front elevation view of a display screen with graphical user interface showing a second embodiment. The broken lines shown in the drawings represent portions of the display screen with graphical user interface that form no part of the claimed design. The outer rectangle shown in broken lines is included for the purpose of showing an unclaimed display screen and forms no part of the claimed design.
